CLAIM

The ornamental design for a ring, as shown and described.

DESCRIPTION

FIG. 1 is a front perspective view of a ring;

FIG. 2 is a top view thereof;

FIG. 3 is a bottom view thereof;

FIG. 4 is a left side view thereof;

FIG. 5 is a right side view thereof;

FIG. 6 is a front side view thereof;

FIG. 7 is a rear side view thereof;

FIG. 8 is a front perspective view of another embodiment of a ring;

FIG. 9 is a top view thereof;

FIG. 10 is a bottom view thereof;

FIG. 11 is a left side view thereof;

FIG. 12 is a right side view thereof;

FIG. 13 is a front side view thereof; and,

FIG. 14 is a rear side view thereof.

The broken lines in the drawings depict portions of the ring that form no part of the corresponding embodiment of the claimed design.

1 Claim, 8 Drawing Sheets(56)
